(57) **CLAIM**

The ornamental design for a medical ultrasound transducer, as shown and described.

DESCRIPTION

FIG. 1 is a perspective view of the medical ultrasound transducer;

FIG. 2 is a front view of the medical ultrasound transducer;

FIG. 3 is a left side view of the medical ultrasound transducer;

FIG. 4 is a right side view of the medical ultrasound transducer;

FIG. 5 is a top view of the medical ultrasound transducer;

FIG. 6 is a bottom view of the medical ultrasound transducer; and,

FIG. 7 is a back view of the medical ultrasound transducer.

The broken line in the interior of the circular element in FIG. 6 is included for the purpose of illustrating environment and forms no part of the claimed design.
